(57) **CLAIM**

The ornamental design for a regulator bonnet, as shown and described.

DESCRIPTION

FIG. 1 is a front, left side perspective of the regulator bonnet showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a cross-sectional view along the line 8-8 in FIG. 6. The broken lines shown in the figures are for the purpose of illustrating portions of the regulator bonnet which form no part of the claimed design.

1 Claim, 6 Drawing Sheets
